UNITED STATES PATENT OFFICE.

RUFUS F. BOOP, OF MILLMONT, PENNSYLVANIA.

PIPE WRENCH.

1,410,794.

Specification of Letters Patent. Patented Mar. 28, 1922.

Application filed March 26, 1920. Serial No. 368,975.

To all whom it may concern:

Be it known that I, RUFUS F. Boop, a citizen of the United States, residing at Millmont, in the county of Union and State of Pennsylvania, have invented certain new and useful Improvements in Pipe Wrenches, of which the following is a specification.

This invention relates to pipe wrenches and has for its primary purpose and object 10 to provide a wrench of this character with improved gripping jaws, capable of substantially embracing the pipe or other objects therebetween so as to give more turning power to the wrench and facilitate its 15 use.

A further and additional object is to provide a wrench of the character above described, embodying improved structural changes, whereby the pressure of the jaws is 20 so evenly distributed as to reduce the possibility of distorting or injuring the objects engaged by the jaws to a minimum.

A further object is to provide a wrench having a movable jaw adjustably supported 25 through a pivoted support carried by the wrench handle; the support being movable about its pivot for causing separation of the wrench jaws to some extent, and for the purpose of adapting the wrench to some 30 particular sized object without the necessity of adjusting the movable jaw.

With the above and other objects in view the invention resides in the details of construction and combination of parts as will 35 hereinafter be more fully described, reference being had to the accompanying drawings, in which—

Figure 1 is a top plan view of the improved wrench.

Figure 2 is a view in side elevation.

Figure 3 is a vertical cross section taken on line 3—3 of Figure 2.

Figure 4 is a detail view illustrating the manner in which the jaws of the device embrace and grip a pipe.

Figure 5 is a detailed view disclosing the manner in which the shank of the movable jaw bears on the head of the handle.

In the drawings, the numeral 1 indicates 50 a wrench handle provided at its forward end with an enlargement, constituting a head, 2 which in the present instance is illustrated as being substantial oval shaped with its curved, forward edge provided with transversely 55 extending and outwardly directed teeth 3. The head 2 provides a support for a pair of

curved jaws 4 and 5 respectively which are fastened rigidly thereto by means of bolts or other suitable fastening elements 6. Each jaw 4 and 5 it will be observed, fits close up 60 against the head 2 on opposite sides and have their front edges curved in alignment with the curved tooth bearing portion 3 of the head, the upper portion 7 however, of each head being of narrower width than its 65 lower portion and tapering to a point or nose 8 which projects forwardly of and above the head 2 as illustrated to advantage in Figure 2 of the drawing. While the rear edge of each stationary jaw may be symmetrically curved as indicated at 9, the forward or working edge is provided with 70 reversely curved tooth-bearing portions 10 and 11 respectively, the teeth of the lower portion being, as previously suggested, in alignment with the teeth of the enlarged head 2.

The adjustable member consists in a curved jaw portion 12 having its inner face provided with teeth 13 pointing oppositely to the teeth formed on the rigid jaws and 80 enlarged heads respectively of the handle. Extending rearwardly from and approximately at right angles to the jaw 12 is an elongated shank 14 which may be square in cross section as indicated in Figure 3 of the 85 drawing and which is provided preferably throughout its length, with threads 15. The shank 14 is adapted to be received in the space between the upper portion 7 of each rigid jaw 4 and 5 so as to ride over the upper end of the head during the adjustment of the movable jaw as indicated in dotted lines in Figure 2, the shank being further supported within a frame or carriage 16 pivotally supported upon the handle 1, rearwardly of the curved edges 9 of the rigid jaws 4 and 5.

This frame consists of the side plates 17 having curved forward edges 18 and opposed openings or windows 19 through which 100 projects the knurled periphery of an adjusting nut 20; the latter embracing the threaded shank 14 of the movable jaw and in threaded engagement therewith. Each plate, moreover, has an extension 21 depending 105 slightly below the handle 1 and joined to a connecting or bridge piece 22. The top connecting wall of the two plates is suitably raised, as at 23 to accommodate the upper end of the adjusting nut 20; the latter being 110 so secured, it will be noted, between the plates that it is permitted to protrude be-

yond the window of each plate to such an extent only as will permit it to be readily revolved for adjustment purposes, without being able to work free of the carriage, even 5 should the shank 14 be entirely withdrawn from the latter. Secured between the plates and at a suitable distance above the upper surface of handle 1 is a longitudinally extending plate 24 against which the free end 10 of a flat spring 25 (as indicated by the dotted line structure of Figure 2), this spring being fastened to the handle at a point slightly remote from the rear of the carriage. The main purpose of this spring is to 15 tensionably exert pressure against the plate 24 for the purpose of normally tending to move the carriage forwardly about its pivot 26. To serve as a counterant to the spring 25 a second spring 27 is pivoted to the under 20 side of the handle, as at 28 with its free end passing inwardly of but in engagement with the bridge 22 of the handle straddling extensions carried by the carriage; this spring 27 being tensioned to exert pressure out- 25 wardly upon the bridge 22 and in a measure counteracting the upward pull of spring 25 so that, as a result, the carriage is normally maintained in a balanced position until, rocked upon its pivot in a clockwise direction 30 by the application of some external force. In which event it is obvious that the position of the shank 14 will be inclined to the axis of the tool and the jaw 12 moved away from the stationary or rigid jaws so as 35 to increase the distance between the respective tooth bearing portions. By reason of such pivotal movement of the carriage it is therefore possible to accommodate pipes of certain sizes between the jaws of the wrench 40 without the necessity of at all times adjusting the movable jaw through the medium of the nut 20. The advantages of this will of course be greater or less, according to the size of the particular object to be gripped 45 by the jaws and the extent to which the movable jaw may be adjusted forwardly of the rigid jaw, at the particular time the occasion arises for the use of the wrench.

The upper portions 7 of the rigid jaw, 50 aside from providing guide ways between which the threaded shank 14 is movable, also provides means whereby pipes of large sizes may be substantially embraced by the gripping portions of the wrench so that upon 55 turning the wrench, the gripping pressure of the respective jaws will not be exerted upon particular points only of the pipe but, on the other hand will be distributed more evenly over a larger area of the pipe section 60 actually embraced by the jaws, permitting the pipes to be turned more easily and without any distortion or injury to the pipe. It is to be remembered that the movable jaw 12 would ordinarily be adjusted forwardly of 65 the rigid jaws 4 and 5, for a considerable

portion of the length of its threaded shank 14 when used in connection with large sized pipes so as to widen the space between the teeth 10 of the rigid jaw portions 7 and the opposed toothed portion 13 of the jaw 12, 70 as indicated in Figure 4. In this way the openings between the jaws is arched or bridged over by the forwardly extending shank portion 14' the latter in conjunction with the oppositely curved tooth bearing 75 portions of the movable and stationary jaws respectively embracing the pipe so that it is firmly gripped at three points, at which points the pressure is approximately equally exerted when the handle 1 is moved to turn 80 the wrench.

In operation, the wrench may be used in the manner and for the purposes for which similar wrenches of this character are adapted. Pipes, nuts or other objects may be inserted between the movable and stationary jaws, to be subsequently clamped firmly by the proper adjustment of the knurled nut 20. In applying the improved wrench to a pipe or other object which is to be turned, 90 the outer jaw 12 is adjusted merely by revolving the nut 20 upon the threaded shank 14, causing the shank to move forwardly through the carriage 16 so that as it rides over the upper end of the head 2 which 95 serves as a bearing for the shank, it carries the jaw 12 away from the tooth bearing portion of the rigid jaws. When the proper adjustment has been made, the wrench may be applied so that the pipe is gripped between the separated jaws and in this connection attention is directed to the fact that the upper portion of the pipe, particularly if it is a large sized one, rests against the under threaded surface of the overhanging 100 shank portion 14'. At the same time, the pipe is gripped about one side by the teeth 13 of the inner curved face of the jaw 12 and on the other side by the teeth of the curved portion and the other side gripped by 105 the teeth 10 of the stationary jaw. Upon adjusting the nut 20 so that the jaws 20 are drawn together to more tightly grip the pipe, it is obvious that pressure is exerted over an extensive area of the circumference 110 of the pipe and consequently upon moving the wrench handle up or down for turning purposes the oppositely directed teeth of the wrench will materially assist in causing the pipes to turn easily with the wrench jaws. 115 With this improved wrench it is unnecessary to always adjust the outer jaw 12 by means of the nut 20 for placing the wrench over a pipe, since by means of the pivotal support, the carriage 16 can be rocked in either direction for swinging the jaw 12 into or away from the stationary jaw, from which it is apparent that when a pipe is of slightly larger a diameter than the space between the lower ends of the outer and inner jaw mem- 120 125 130

bers, pressure applied to the end of the shank 14 will depress the carriage downwardly and swing the jaw 12 outwardly to enlarge the opening and permit the pipe 5 to pass therein, subsequent to which release of pressure upon the spring 5, will enable spring 5 to return the carriage to its normal position, forcing jaw 12 inwardly against the pipe. At the point where the 10 strain upon the handle is ordinarily the greatest, it is to be noted that in the present invention, cushioning means are provided for taking up the shock incident to the use of a device of this character. The 15 springs 25 and 27 not only serve to resiliently support the carriage 16 but also act as buffers or shock absorbers for relieving the handle of any direct shock or strain. Attention is called to the fact that during the 20 reciprocatory movement of handle 1, the spring on each side acts as a cushion to prevent the snapping off of the handle by any such jerk or jar. Nuts, bolts, and small sized objects of any degree may be firmly clamped 25 between the jaws of this wrench since it is of course possible to adjust the outer jaw 12 into close proximity and even contact with the tooth bearing portion of the head 2, consequently the opening between the jaws may 30 be contracted to any desired degree as illustrated to advantage in Figure 2 of the drawing.

From the foregoing description it should be clear that the present invention contemplates a device not only capable of and adapted to the uses to which structures of this character are ordinarily applied but one which embodies improved features of construction which enlarges its field of usefulness and which renders it more efficient and satisfactory tool. It is to be understood of course, that minor changes in the construction and arrangement of parts may be resorted to as fall within the scope of the 45 invention as defined in the claims appended.

What I claim as new and desire to secure by Letters Patent is:—

1. A wrench, comprising a handle having an enlarged head at one end, the outer end 50 of which is curved, an outer curved jaw adapted to fit snugly against the curved outer end of the enlarged head, a shank integral with said outer curved jaw and

extending rearwardly therefrom over one end of the said enlarged head, a carriage pivoted to said handle for engaging and supporting said shank, and inner jaw members rigid to said enlarged head on opposite sides thereof extending beyond the shank on opposite sides, each of said jaw members having its outer surface provided with a 60 reversely curved jaw portion, one of which portions is in alignment with the curved outer end of the said head.

2. A wrench, including a handle having one end enlarged to provide a jaw support, the lower front surface of said jaw support being provided with teeth, a pair of curved jaws rigidly affixed to said support on opposite sides, each of said jaws tapering to provide a nose portion projecting in a curve beyond the head, an adjustable member comprising a curved jaw having its shank portion inserted between the nose portions of the curved or rigid jaws, a carriage supported upon said handle for engaging the end of the said shank and means carried by said carriage for adjusting said movable jaw outwardly from the rigid jaws, whereby the space between the adjustable and rigid jaws 80 may be bridged by a portion of the shank to provide an additional gripping surface.

3. A pipe wrench comprising a headed handle having a fixed jaw at the head end disposed at right angles thereto, a movable jaw opposed to the fixed jaw having a shank extending parallel with the handle and rearwardly of the fixed jaw, the said fixed jaw having a clearance space provided therethrough to permit passage of the said shank and the head of the handle providing a bearing for the shank, said fixed and movable jaws having inner opposing portions of the jaw spaces concaved to provide gripping surfaces for engaging a pipe over a 95 suitable area of the circumference, and means on the said handle for adjusting the movable jaw, said means including a frame pivoted to the handle and supportably engaging the shank of the movable jaw.

In testimony whereof I affix my signature in presence of two witnesses.
